UNITED STATES PATENT OFFICE.

THEODORE GENSMER, OF PORTLAND, OREGON, ASSIGNOR TO ROBERT Z. FARMER, OF PORTLAND, OREGON.

LAWN SPRINKLER.

Application filed February 20, 1923. Serial No. 620,285.

To all whom it may concern:

Be it known that I, THEODORE GENSMER, a citizen of the United States, and a resident of the city of Portland, in the county of Multnomah and the State of Oregon, have invented a new and useful Improvement in a Lawn Sprinkler, of which the following is a specification.

This invention relates to new and useful improvements in lawn sprinklers.

The primary object of the invention is to provide a sprinkler which will diffuse the streams of water discharged therefrom into the finest possible units and will evenly distribute the same over a very large area.

A further object of the invention is to provide a sprinkler which may be adjusted to vary the area covered during operation irrespective of the amount of water discharged or the pressure at which the water is fed to the device.

A still further object of the invention is to provide a sprinkler constructed of a minimum number of separable parts, which may be easily repaired or replaced.

Another object of the invention is to provide a sprinkler of the above noted type which, when placed, will remain in operative position, and one which will operate easily and with a minimum amount of friction.

Other objects and advantages of the invention will be apparent during the course of the following description.

In the accompanying drawing forming a part of this specification and in which like numerals are employed to designate like parts throughout the same,

Figure 1 is a side elevational view of the assembled sprinkler with a hose connection for feeding water thereto from a source of water supply, not shown,

Figure 2 is a plan view of the sprinkler head showing the diffusing blades and the nozzles for impinging the water against the same,

Figure 3 is a partial cross-sectional view thru the head of the sprinkler and shows the internal construction of the same,

Figure 4 is a plan view of the nozzles thru which the water is discharged for sprinkling purposes, the dotted positions illustrating the adjustments obtainable to increase or decrease the diameter of the

space over which the water will be diffused, 55 and

Figure 5 is an end elevational view of the nozzles of the sprinkler head without the diffusing means employed in connection therewith, the dotted positions showing the 60 adjustments of the nozzle outlets.

Briefly described, my sprinkler device includes a tubular standard or support upon which a sprinkler head is rotatably mounted. During periods of idleness, the sprinkler head rests upon a supporting portion of the tubular standard, but upon being placed in operation, the sprinkler head is automatically elevated above the said supporting portion and rotates freely about a pivot 70 member. This sprinkler head includes a suitable number of discharge nozzles which are independently adjustable for directing the streams of water against a plurality of diffusing surfaces at different elevations, 75 thereby causing the streams to be broken up into fine particles and deposited over areas of different radii. The plurality of diffusing surfaces are carried by a disk rotatably mounted on the nozzle carrying portion of 80 the sprinkler head and, during operation, revolve in the direction opposite to that taken by the nozzles during their travel about the supporting standard.

It is to be understood that the disk with 85 its diffusing surfaces may be dismounted from the nozzle carrying portion of the sprinkler head and the device successfully operated without the same. The spray, however, does not consist of as finely divided particles of water when the diffusing surfaces are not used as when the said surfaces form a part of the operative device.

For a better and more complete detailed 90 description of my sprinkler, reference is had to the accompanying drawings wherein for the purpose of illustration is shown a preferred embodiment of this invention. The numeral 1 designates a hose or other tubular 95 conducting member thru which water is conveyed from a source of supply, not shown. This hose 1 is provided with a screw attachment means or connection by means of which it may be removably fastened to the nipple 3 carried by one opening of the T-coupler 4. One of the remaining 100 openings of this T-coupler 4 is threadedly connected to a tubular standard or shaft 105

5, while the remaining opening of the T-coupler is threadedly connected to a section of piping 6 which is externally screw-threaded at its upper end and internally screw-threaded at its lower end. The lower, internally screw-threaded end of this member 6 is adapted to be connected to the rod 7, having a pointed lower end 8, by means of the external screw threads 9 formed on 10 the said rod. A collar or disk 10 is selectively threaded upon the threaded portion 9 of the rod 7 and acts as a stop when the rod 8 is driven into the soil underneath the lawn to be sprinkled by the device. It is to be understood that the threaded portion 9 of the rod 7 permits the latter to be telescopically connected with the piping 6 so that the said rod will project therefrom for different portions of its length, thereby 15 providing a rod of suitable length to adapt the same to be driven into soil of different degrees of hardness. The collar 10 threaded upon the rod 9 may be employed, also, as a lock nut for preventing the rod 7 from becoming loose from the piping 6.

The upper end of the tubular standard or shaft 5 is internally screw threaded for being connected to the threaded end 18 of the tubular bushing 17 having the bore 17^a 20 and the enlarged head 16. This tubular bushing is employed for loosely connecting the nipple 11 to the tubular standard or shaft 5 for permitting the said nipple to freely rotate about the bushing 17 and to move axially in respect thereto. This nipple 11 is threaded at its upper end 12 for connection with the threads 12^a of the hollow hexagonally-shaped member 14. The bore of this member 14 is of relatively large 25 diameter to form the recess or chamber 15 while the remaining portion 14^a of the bore of the member 14 is of less diameter than the recess or chamber 15.

Threadedly connected to the upper portion 30 of the hexagonal member 14 and in horizontal alinement with the reduced portion 14^a of the bore of the member 14 are the inner threaded ends of the nozzle members 19 and 20. These nozzles are crooked or bent upon themselves at their outer ends 35 for causing the streams of water discharged therefrom to be directed substantially radially inwardly. In Figs. 4 and 5 these nozzles are shown in full and dotted line positions for illustrating the adaptability of the nozzles to be rotated, by means of their threaded connections with the member 14, to permit the discharge extremities of the said nozzles to be located at different elevations.

Threadedly connected to the upper end 40 of the member 14 is a bolt 21 having rotatably mounted thereon a two-part collar bushing 22 which is employed for clamping the disk 23 therebetween. This disk is pro-

vided with struck up fins or projections 24 which extend tangentially in respect to the axis of the disk. While these fins or projections 24 are shown as having upper contours constituting segments of circles, it 70 is to be understood that I do not desire to limit myself to this particular formation as many other contours or shapes will give as equally good results.

The operation of this sprinkler may be 75 described as follows:—

It is to be understood that the sprinkler is first properly located in respect to the portion of a lawn to be sprinkled and the rod portion 9 is driven into the soil at that 80 point. The water supply is then connected with the hose 1 and the flow of water started. The water in passing upwardly thru the hollow standard 5 will pass thru the bore 17^a of the bushing 17 and will enter the 85 recess or chamber 15 and the bore 14^a. This upward pressure of water will cause the members rotatably connected to the hollow standard 5 by means of the bushing 17 to be elevated for producing a gap at 13 be- 90 tween the lower end of the nipple 11 and the upper end of the hollow standard or shaft 5. The said nipple 11 will then rotate about the bushing 17 with very little resistance. The streams of water discharged 95 from the nozzles 19 and 20 will be directed against the diffusing fins or projections 24 and will be broken up into finely divided particles and sprayed over a large area of lawn. The nozzles will be caused to rotate 100 in one direction while the streams of water impinging against the fins or projections 24 will cause the disk 23 to rotate in the opposite direction. It will be understood that by adjusting the nozzles 19 and 20 so 105 that their discharge extremities will be positioned on different elevations, the water will be diffused or sprayed over different sized areas.

In Figs. 4 and 5 the sprinkler embodying 110 this invention is illustrated without the disk 23 and the diffusing fins or projections 24. When the said disk 23 is done away with, the device may be used successfully, but a different sprinkling effect is obtained. The 115 nozzles may be adjusted so that the streams of water discharged therefrom will merely be thrown outwardly from the standard 5, or the said nozzles may be adjusted so that the streams of water discharged therefrom 120 will impinge against each other and be broken up into a fine spray.

It is to be understood that the forms of this invention herewith shown and described are to be taken as preferred examples of the 125 same, and that various changes in the shape, size, and arrangement of parts may be resorted to without departing from the spirit of the invention or the scope of the subjoined claims.

Having thus described the invention, I claim:—

1. In a device of the type described, a hollow standard, means for feeding water thereto, a hollow head rotatably mounted thereupon, a disk having a plurality of fins rotatably carried by said head, and a plurality of nozzles carried by said head and adjustable to discharge water against said fins at different elevations.
2. In a device of the type described, a hollow standard, a hollow head rotatably mounted thereon and movable axially in respect thereto, a disk having a plurality of fins rotatably carried by said head, and a plurality of nozzles carried by said head and adjustable to discharge water against said fins at different elevations.
3. In a device of the type described, a hollow standard, means for feeding water thereto, a hollow head rotatably mounted thereon, a disk having a plurality of struck-up fins rotatably carried by said head, and a plurality of nozzles carried by said head and adjustable to discharge water against said fins at different elevations.
4. In a device of the type described, a hollow standard, means for feeding water thereto, a hollow head rotatably mounted thereon and movable axially in respect thereto, a disk having a plurality of struck-up fins rotatably carried by said head, and a plurality of nozzles carried by said head and adjustable to discharge water against said fins at different elevations.
5. In a device of the type described, a tubular standard, a hollow head rotatably mounted thereon, a disk having a plurality of struck-up tangentially extending fins carried by said head and rotatable in respect
- thereto, and a plurality of reaction nozzles carried by said rotatable head and disposed to cause rotation of said head and to discharge water against said fins to cause said disk to rotate in an opposite direction from 45 said head.
6. In a device of the type described, a vertically extending conduit having external threads at its upper end, a bushing threadedly connected to the upper end of said conduit, a head rotatably carried by said bushing, a disk carried by said head to rotate in respect thereto and having fan-like blades projecting upwardly therefrom, and reaction nozzles adjustably carried by 55 said rotatable head and disposed to cause rotation of said head and to discharge water against said fan-like blades to cause said disk to rotate in an opposite direction from 60 said head.
7. In a device of the type described, a perpendicular tubular standard adjustable longitudinally, means for feeding water to the bore of said standard, a head rotatably mounted upon said standard and having a 65 pocket for the reception of water from the standard, a plurality of discharge nozzles adjustably carried by said head for enabling the extremities of the same to be positioned at different elevations, and a disk having 70 struck-up fins rotatably carried by said head and adapted to diffuse the water discharged from said nozzles.

In testimony that I claim the foregoing as my own I hereunto attach my signature 75 in the presence of two witnesses.

THEODORE GENSMER.
